UNITED STATES PATENT OFFICE.

GEORGE H. LENNON, OF BALTIMORE, MARYLAND.

TOY BENCH OR SETTEE.

SPECIFICATION forming part of Letters Patent No. 763,617, dated June 28, 1904.

Application filed November 10, 1903. Serial No. 180,588. (No model.)

To all whom it may concern:

Be it known that I, GEORGE H. LENNON, a citizen of the United States, residing at Baltimore city, in the State of Maryland, have invented certain new and useful Improvements in Toy Benches or Settees, of which the following is a specification, reference being had therein to the accompanying drawings.

My invention relates to toy benches or settees; and my object is to construct a bench or settee composed partly of sheet metal and partly of wood without the use of nails or brads and collapsible, so that they will be convenient for packing and, further, can be manufactured expeditiously and at a very small cost. I attain these results by means of the structure shown in the accompanying drawings, in which—

Figure 1 is a perspective view of a toy bench or settee embodying my invention. Fig. 2 is an end view of the same. Fig. 3 is an enlarged cross-section view through one of the wooden top plates at R. Fig. 4 is an enlarged view of the supporting portion, showing clamp. Figs. 5 and 6 are detail views of the construction.

The seat and back of the toy bench or settee are formed of strips of wood C C C, Fig. 1. The supporting portions and legs of the bench are formed from strips of sheet metal A D B, Figs. 2 and 6, in the style of bench shown being bent nearly in the shape of the letter S, the lower portion of the S being bent downward and flanged to form the leg A and the upper portion being bent backward and doubled along itself d d, Fig. 2, forming the back clamped at F and the remaining portion flanged and bent to form the back leg. Two similar supporting portions are used near each end of the wood strips.

In forming the toy bench or settee the sheet-metal strips are stamped as shown in Fig. 6, having dart-shaped points K K K struck up out of and approximately at right angles to the plane of the blank of sheet metal, having a similar projection F made in the opposite direction having a hole stamped at G, and having portions A and B of sufficient length to form the

legs of the bench or settee. Wooden strips are then impaled on the first-named points. (The 50 position of a projection in one of the wooden strips is shown in Fig. 3.) The sheet metal is then bent so that the portion d d B folds back and is doubled along itself and so that projection F enters the hole G. The projection F 55 is then bent over and clamped, as shown in Fig. 4. A like piece is attached to the same side of the wood strips near the opposite ends. The article then has the shape shown in Fig. 5 and is in a form convenient for packing. 60 Any desired shape may then be given the bench by bending the sheet metal and by varying the number of wooden strips used as seat and back portions. The legs may be straight or shaped or bent in any suitable or well-known manner.

Having described my invention, what I claim as new, and desire to secure by Letters Patent, is—

1. A flexible toy bench or settee constructed 70 as described, and consisting of wood strips C, C, C, and supporting portions of thin, semi-rigid but foldable sheet metal, D, d, d, having points R, R, projected out thereof and into said wooden strips C, C, C, connecting the 75 supporting portions, said supporting portions having one extension, A, forming the front legs, and another extension d, d, bent back upon itself forming the support of the back of the bench and secured by a dart-shaped 80 point F, broken out of the sheet metal in an opposite direction from the first-named points and clamped through the hole G in the last-named extension, and a portion, B, of the last-named extension forming the rear legs of the 85 bench.

2. A toy bench or settee composed of wood top plates, forming seat or back, and two supporting-frames of sheet metal having dart-shaped points projected out of the sheet metal 90 and penetrating the wood top plates, said frames having one extension forming the front legs, and another extension of the sheet metal bent back upon itself forming the support of the back of the bench and secured by a dart-shaped point broken out of the sheet metal in 95

an opposite direction from the first-named points and clamped through a hole in the last-named extension, and a portion of said last-named extension forming the rear legs of the 5 bench.

In testimony whereof I have hereunto signed my name, in the presence of two wit-

nesses, at Baltimore city, in the State of Maryland, this 6th day of November, 1903.

GEORGE H. LENNON.
